UNITED STATES PATENT OFFICE.

CEDRIC P. SIBLEY, OF DETROIT, MICHIGAN.

PAPER FASTENER.

Application filed December 26, 1922. Serial No. 608,857.

To all whom it may concern:

Be it known that I, CEDRIC P. SIBLEY, a citizen of the United States, residing at Detroit, in the county of Wayne and State 5 of Michigan, have invented certain new and useful Improvements in Paper Fasteners, of which the following is a specification.

This invention relates to paper fasteners and has for its object what might be termed 10 a gang paper fastener of the prong type. So far as I am aware, no one has heretofore made a prong type fastener suitable for an automatic or semi-automatic feed into a punching machine. This I have accomplished by designing a blank which may be punched out of sheet metal stock and the prongs then formed over by suitable dies to form a gang of prong fasteners that may be successively driven through the paper 20 stock and sheared off.

For the purpose of illustration, I have shown my gang fasteners as improvements of the fasteners shown in the prior Sibley Patent No. 759,440.

25 In the drawings:

Fig. 1 is a side elevation of the gang.

Fig. 2 is an end elevation of the same.

Fig. 3 is a cross section taken on the line 3—3 of Fig. 1.

30 Fig. 4 shows how the gang of prong fasteners is laid out on the sheet metal for the punching operation.

Fig. 5 shows a modified form of lay out.

Fig. 6 is a perspective showing how the 35 fasteners are driven into the paper stock.

A plurality of slotted cup-shaped heads *a* are stamped out of a sheet of metal leaving the ties *c* to connect the heads. These heads have on either side the prongs *e*. These 40 prongs are pressed up under the heads as shown in Fig. 3 at *d* to anchor the prongs to the heads in a suitable position. The slot *f* serves to allow the punch *x* to be driven through the head and between the 45 prongs into the paper stock so as to cut the hole ahead of the fastener. The legs or prongs of the fastener cling to the side of the punch and follow the same through the paper stock and may be turned up by the 50 fingers after the punch is withdrawn. The small points *h* pressed out of the legs or prongs serve to retain the fastener in the hole after the punch has started back.

In the lay-out shown in Fig. 4 the gangs 55 of prong fasteners may be cut out of the metal stock with very little waste as the

prongs of one gang overlap with the next adjacent gang.

The lay-out shown in Fig. 5 will achieve even greater economy in stock but the 60 fasteners will have to be fed into the machine on the bias.

It will be understood that any suitable punching machine can be used to successively apply the fasteners to the paper 65 stock. Only a punch is shown here in the drawings to show how the tool is used. The machine itself may be automatically or semi-automatically fed by forcing the gang of fasteners forward at every application 70 of the punch. By "semi-automatically" I mean a suitable guide is provided while the gang of fasteners is pushed forward with the fingers.

A stationary anvil *k* is carried by the machine which is projected under the gang of fasteners. The anvil and plunger co-operate together to cut a fastener from the gang by shearing across the tie portion *c*. 75

It will be noted that the ties *c* not only 80 tie the pronged heads together so that the fasteners may be fed into the driving machine, but they serve to position the slots and the prongs with respect to the machine and with respect to the work. For instance, it 85 is important that the slots *f* in the heads of the fasteners be always properly positioned so that the punch can drive down through the slot. Heretofore this has had to be done by hand in such a machine as 90 shown in the Sibley Patent No. 759,400. It is also necessary to have the prongs always in a predetermined position with respect to the punch. The ties serve to so 95 position the fasteners that both the prongs and the slots will properly line up with the punch.

What I claim is:

1. A gang of fasteners for use in a fastener driving machine provided with a punch, comprising a plurality of heads each provided with an elongated slot and each head provided with a pair of prongs with outer free ends, and ties connecting the heads directly together, independently of 100 the prongs and serving not only to join the heads but also being arranged so that the slots in the heads all occupy the same relative position so that each elongated slot will always be presented in proper registering position with the punch. 105

2. A gang of fasteners for use in a

fastener driving machine provided with a paper piercing punch, comprising a plurality of heads each provided with an elongated slot, each head provided with a pair of folded together prongs and integral ties independent of the prongs connecting together the heads at the rims, the said ties serving to form both a continuous line of

heads and also serving to position both the elongated slots and prongs so that they occupy the same general relative position in each fastener, whereby they are correctly presented to the punch and to the work. ¹⁰

In testimony whereof I affix my signature.

CEDRIC P. SIBLEY.
